UNITED STATES PATENT OFFICE.

LEWIS A. LIPMAN, OF BROOKLYN, NEW YORK.

DESIGN FOR AN ALBUM.

SPECIFICATION forming part of Design No. 20,568, dated March 10, 1891.

Application filed January 10, 1891. Serial No. 377,371. Term of patent 3½ years.

To all whom it may concern:

Be it known that I, LEWIS A. LIPMAN, a citizen of the United States, residing at Brooklyn, in the county of Kings and State of New York, have invented and produced a new and original Design for an Album, of which the following is a specification, reference being had to the accompanying photographs, forming part thereof.

Figure 1 represents a face view of an open album embodying my design, and Fig. 2 represents a back view of the same.

The design consists of two figures A and B,

each representing one section of a bisected heart, which sections appear connected by a hinge-like figure. The combined marginal contour of the two figures A and B simulates that of a heart.

I claim—

The design for albums herein shown and described.

LEWIS A. LIPMAN.
